UNITED STATES PATENT OFFICE.

FRANCIS R. WARDLE, OF NEW YORK, N. Y.

DESIGN FOR A BOTTLE.

SPECIFICATION forming part of Design No. 19,798, dated April 29, 1890.

Application filed March 29, 1890. Serial No. 345,895. Term of patent 14 years.

To all whom it may concern:

Be it known that I, FRANCIS R. WARDLE, a citizen of the United States of America, residing in the city, county, and State of New York, have invented and produced a new and original Design for Bottles, of which the following is a specification, reference being had to the accompanying drawing.

The feature which constitutes my invention consists in the shape of the bottles and the diagonally-fluted and smooth surfaces, as hereinafter explained, and as shown in the drawing, in which the figure shows the bottle in side elevation.

The body A of the bottle is formed approximately cylindrical, but slightly tapering from the upper part to the bottom on curved lines. The upper part of the body is contracted into

a straight neck surmounted by a plain horizontal flange. The body has diagonal or spiral flutings b, which are rounded and extend from top to bottom of the body. The shoulder C and neck D of the bottle are plain..

I claim--

The design for a bottle herein described and shown, consisting of the body A, slightly tapering downward from the top and fluted diagonally or spirally, with the plain shoulders and plain straight neck.

In testimony whereof I have signed my name to this specification in the presence of two subscribing witnesses.

FRANCIS R. WARDLE.
